Primary Examiner — Mojtaba Tehrani(57) **CLAIM**

The ornamental design for a paintbrush cleaner, as shown and described.

DESCRIPTION

1. Paintbrush cleaner
- 1.1: Top perspective;
- 1.2 : Elevation;
- 1.3 : Elevation;
- 1.4 : Elevation;
- 1.5 : Elevation;
- 1.6 : Top;
- 1.7 : Bottom;
- 1.8 : Top perspective;
- 1.9 : Elevation;
- 1.10 : Elevation;
- 1.11 : Elevation;
- 1.12 : Elevation;
- 1.13 : Top;
- 1.14 : Bottom.

The reproductions 1.1-1.7 disclose a paintbrush cleaner in an open configuration, while reproductions 1.8-1.14 disclose the paintbrush cleaner in a closed configuration.

The broken line in the reproductions discloses unclaimed portion of the paintbrush cleaner only and forms no part of the claimed design.

1 Claim, 14 Drawing Sheets(56)
